US00D864989S

(12) **United States Design Patent** (10) Patent No.: **US D864,989 S**
 Lepine et al. (45) Date of Patent: **** Oct. 29, 2019**

(54) **COMPUTER DISPLAY WITH HOME SCREEN**

(71) Applicant: **DEKA Products Limited Partnership**, Manchester, NH (US)

(72) Inventors: **Allison E. Lepine**, Concord, NH (US); **Constance D. Pitenis**, Hooksett, NH (US); **Eric N. Sabin**, Manchester, NH (US)

(73) Assignee: **DEKA Products Limited Partnership**, Manchester, NH (US)

(**) Term: **15 Years**

(21) Appl. No.: **29/661,806**

(22) Filed: **Aug. 30, 2018**

Related U.S. Application Data

(62) Division of application No. 29/579,660, filed on Sep. 30, 2016, now Pat. No. Des. 830,384.
